(57) **CLAIM**

The ornamental design for a punch and punch retainer with orientation features, as shown and described.

DESCRIPTION

FIG. 1 is a first perspective view of a first embodiment of a punch and punch retainer with orientation features in accordance with the present invention;

FIG. 2 is a second perspective view of the punch and punch retainer with orientation features of FIG. 1 from a different direction;

FIG. 3 is a top view of the punch and punch retainer with orientation features of FIGS. 1 and 2;

FIG. 4 is a bottom view of the punch and punch retainer with orientation features of FIGS. 1-3;

FIG. 5 is a first side view of the punch and punch retainer with orientation features of FIGS. 1-4;

FIG. 6 is a second opposite side view of the punch and punch retainer with orientation features of FIGS. 1-5;

FIG. 7 is front view of the punch and punch retainer with orientation features of FIGS. 1-6;

FIG. 8 is a rear view of the punch and punch retainer with orientation features of FIGS. 1-7;

FIG. 9 is a first perspective exploded view of the punch and punch retainer with orientation features of FIGS. 1-8;

FIG. 10 is a second perspective exploded view of the punch and punch retainer with orientation features of FIGS. 1-9 from a different direction;

FIG. 11 is a first perspective view of a second embodiment of a punch and punch retainer with orientation features in accordance with the present invention;

FIG. 12 is a second perspective view of the punch and punch retainer with orientation features of FIG. 11 from a different direction;

FIG. 13 is a top view of the punch and punch retainer with orientation features of FIGS. 11 and 12;

FIG. 14 is a bottom view of the punch and punch retainer with orientation features of FIGS. 11-13;

FIG. 15 is a first side view of the punch and punch retainer with orientation features of FIGS. 11-14;

FIG. 16 is a second opposite side view of the punch and punch retainer with orientation features of FIGS. 11-15;

FIG. 17 is front view of the punch and punch retainer with orientation features of FIGS. 11-16;

FIG. 18 is a rear view of the punch and punch retainer with orientation features of FIGS. 11-17;

FIG. 19 is a first perspective exploded view of the punch and punch retainer with orientation features of FIGS. 11-18;

FIG. 20 is a second perspective exploded view of the punch and punch retainer with orientation features of FIGS. 11-19 from a different direction;

(Continued)

FIG. 21 is a first perspective view of a third embodiment of a punch and punch retainer with orientation features in accordance with the present invention;

FIG. 22 is a second perspective view of the punch and punch retainer with orientation features of FIG. 21 from a different direction;

FIG. 23 is a top view of the punch and punch retainer with orientation features of FIGS. 21 and 22;

FIG. 24 is a bottom view of the punch and punch retainer with orientation features of FIGS. 21-23;

FIG. 25 is a first side view of the punch and punch retainer with orientation features of FIGS. 21-24;

FIG. 26 is a second opposite side view of the punch and punch retainer with orientation features of FIGS. 21-25;

FIG. 27 is front view of the punch and punch retainer with orientation features of FIGS. 21-26;

FIG. 28 is a rear view of the punch and punch retainer with orientation features of FIGS. 21-27;

FIG. 29 is a first perspective exploded view of the punch and punch retainer with orientation features of FIGS. 21-28;

FIG. 30 is a second perspective exploded view of the punch and punch retainer with orientation features of FIGS. 21-29 from a different direction;

FIG. 31 is a first perspective view of a fourth embodiment of a punch and punch retainer with orientation features in accordance with the present invention;

FIG. 32 is a second perspective view of the punch and punch retainer with orientation features of FIG. 31 from a different direction;

FIG. 33 is a top view of the punch and punch retainer with orientation features of FIGS. 31 and 32;

FIG. 34 is a bottom view of the punch and punch retainer with orientation features of FIGS. 31-33;

FIG. 35 is a first side view of the punch and punch retainer with orientation features of FIGS. 31-34;

FIG. 36 is a second opposite side view of the punch and punch retainer with orientation features of FIGS. 31-35;

FIG. 37 is front view of the punch and punch retainer with orientation features of FIGS. 31-36;

FIG. 38 is a rear view of the punch and punch retainer with orientation features of FIGS. 31-37;

FIG. 39 is a first perspective exploded view of the punch and punch retainer with orientation features of FIGS. 31-38; and,

FIG. 40 is a second perspective exploded view of the punch and punch retainer with orientation features of FIGS. 31-39 from a different direction.

The broken lines are directed to unclaimed subject matter and are for illustrative purposes only; the broken lines form no part of the claimed design.
